United States Patent Office

Des. 191,313
Patented Sept. 12, 1961

191,313

GAME BOARD

William J. Brozovich, 10529 Buford Ave.,
Inglewood, Calif.

Filed Oct. 18, 1960, Ser. No. 62,535

Term of patent 3½ years

(Cl. D34—5)

The drawing is a plan view of a game board showing my new design.

The game board of my new design is of conventional thickness.

I claim:

The ornamental design for a game board, as shown and described.
